Attorney:

UNITED STATES PATENT OFFICE.

COLUMBUS B. MCPHERSON, OF BIRMINGHAM, ILLINOIS.

TELEPHONE-SWITCH.

SPECIFICATION forming part of Letters Patent No. 709,351, dated September 16, 1902.

Application filed March 12, 1902. Serial No. 97,911. (No model.)

To all whom it may concern:

Be it known that I, COLUMBUS B. MCPHERSON, a citizen of the United States, residing at Birmingham, in the county of Schuyler 5 and State of Illinois, have invented certain new and useful Improvements in Telephone-Switches; and I do hereby declare the following to be a full, clear, and exact description of the invention, such as will enable others 10 skilled in the art to which it appertains to make and use the same.

This invention relates to telephone-switches, the object in view being to provide a switch or cut-out by means of which a telephone 15 may be thrown out of the main circuit during a severe electrical storm for the purpose of preventing the wrecking or burning out of the instrument. The elements of the switch are so combined and arranged that 20 they will not interfere with other telephones on the main line which may continue in operation, notwithstanding the fact that any particular telephonic instrument has been cut out of the main circuit.

With the above object in view the invention 25 consists in the novel construction, combination, and arrangement of parts herein-after fully described and claimed.

In the drawings, Figure 1 is a perspective 30 view of a telephone-switch embodying the features of the invention. Fig. 2 is a perspective view of a modified form of the switch.

The improved switch comprises a bracket 35 1, forming the support for the members of the switch, said bracket comprising, essentially, a vertical member 1^a and a cross-head or top horizontal member 2, suitably fastened together, forming a T-shaped bracket provided with openings 3 for the reception of 40 spikes or other suitable fasteners by means of which the bracket may be secured to a pole, standard, or the exterior of a house, barn, or other building.

In carrying out the present invention a 45 switch-lever 4 is provided, which is substantially semicircular in form to provide the necessary resiliency for holding the free end of the lever in electrical contact with one of the binding-posts. At one end the switch-lever is fulcrumed on a journal-post 5 and 50 held in place by washers 5^a, the post 5 con-

stituting one of the binding-posts of the device. The lever at its opposite end is bent into the form of a loop or eye 6 and is adapted to bear against a lever rest or contact 7, 55 preferably in the form of a flat strip of metal having one end bent at an angle to form a limiting shoulder or stop 8, while the opposite end is deflected inward to form a bevel surface 9, against which the free end of the 60 switch-lever may ride while bringing the same into engagement with the stop-shoulder 8. The lever-rest 7 is mounted upon the extremity of a binding-post 10, projecting outwardly from one end of the cross-head 2. 65

At or near the lower end of the upright 1^a is arranged a third binding-post 11, which receives and has electrically connected therewith a ground-wire 12, by which the current is carried to the ground. Adjacent to the 70 binding-post 11 is a post 13, projecting from the bracket and bearing at its free end a lever-rest 14, similar in all respects to the rest 7, hereinabove described. A wire leading from the main-circuit wire through the telephone 75 and back to the main line is severed at a suitable point, and one end 15 thereof is electrically connected to the journal-post 5 or the modified form of the latter herein-after set forth, while the other end 16 is connected 80 to the binding-post 10. By rocking the switch-lever on the journal-post 5 as a center and bringing said lever into engagement with the rest 7 the telephone is placed in circuit.

During the progress of a severe electrical 85 storm the switch-lever 4 is oscillated so as to move the free end thereof out of engagement with the rest 7 and into engagement with the other rest 14. This has the effect of cutting out the telephone from the circuit, 90 so that it will not be affected by an excessive current passing along the main-line wires, the current passing from the main line through the wire 15 and switch 4 to the binding-post 13, from which it jumps to the adjacent post 11, and from the latter it is carried to the ground by means of the wire 12. 95

The form of the device shown by Fig. 2 is similar in the main to that shown by Fig. 1 and has like numerals applied thereto. The 100 difference in construction in the device shown by Fig. 2 is that the fulcrumed end of the

lever 4 is bent at an angle to form a fulcrum-post 17, which is rotatably mounted in the member 2.

In the form of the device shown by Fig. 1 5 the rests 7 and 14 are provided with outstanding beveled retaining-ribs 17, having inner abrupt ends 18, forming shoulders against which one edge of the switch-lever 4 is adapted to bear to prevent accidental displacement 10 of said lever. These ribs will also be applied at times to the form of the device shown by Fig. 2.

Having thus fully described the invention, what is claimed as new is—

15 1. The combination with a bracket having a plurality of binding-posts secured thereto, of a semicircular spring switch-lever having one of its ends fulcrumed and the other free for oscillatable movement, and a lever-rest 20 secured upon said bracket adjacent to one of said binding-posts and having a curved bearing-face and a stop.

2. The combination with a bracket having a plurality of binding-posts secured thereto, 25 of a semicircular spring switch-lever having one of its ends bent at an angle to be inserted in said bracket to form a combined binding-

post and journal, and a lever-rest secured upon said bracket adjacent to one of said binding-posts, and having a curved bearing- 30 face having one of its ends bent to form a stop.

3. The combination with a bracket, of a binding-post mounted upon the upper end thereof, a curved bearing-surface secured to 35 said binding-post and having one of its ends bent to form a stop, a spring switch-lever having one of its ends bent at an angle and inserted in the bracket to form a combined binding-post and journal, a third binding-post 40 secured to the lower end of the bracket, electric connections secured to said binding-post, and a lever-rest secured upon said bracket.

4. The combination of a bracket having a plurality of binding-posts secured thereto, 45 lever-rests contiguous to the posts and provided with shouldered retaining-ribs, and a lever movable over the bracket.

In testimony whereof I affix my signature in presence of two witnesses.

COLUMBUS B. MCPHERSON.
